UNITED STATES PATENT OFFICE

GEORGE A. MARKS, OF CHICAGO, ILLINOIS

DESIGN FOR A COMBINED LAMP ARM AND BASE

Application filed April 16, 1931. Serial No. 39,503. Term of patent 3½ years.

To all whom it may concern:

Be it known that I, GEORGE A. MARKS, a citizen of the United States, residing at Chicago, in the county of Cook and State of Illinois, have invented a new, original, and ornamental Design for a Combined Lamp Arm and Base, of which the following is a specification, reference being had to the accompanying drawings, forming part thereof.

Figure 1 is a front view of a combined lamp arm and base, showing my new design.

Figure 2 is a side view of same, showing my new design.

Figure 3 is a view of the base portion forming a part of the design shown in Figures 1 and 2 with the lamp arm omitted.

I claim:

The ornamental design for a combined lamp arm and base, as shown.

GEORGE A. MARKS.
